VENT LOCKING MEANS FOR AWNING TYPE WINDOWS

Morton Tucker, Hialeah, Fla.

Application June 25, 1958, Serial No. 744,411

2 Claims. (Cl. 268—111)

This invention relates to window devices and particularly to that type of window device commonly recognized in the industry as an awning type window and that is composed of a plurality of horizontally pivoted and vertically swinging vents that are movable to and from an overlapping relation with respect to each other.

Window devices of the above noted characters have generally had one outstanding fault, such being the absence of any definite locking means for the several vents that prevents unauthorized movement of the vents outwardly by the use of a tool or other device that is capable of prying the vents open, it being understood that this is possible to a certain extent due to the fact that the vents are swung by linkage devices that are relatively long and flexible and that are not capable of maintaining the vents fully closed and sealed against movement to a limited degree.

The invention contemplates individual lock members for each end of each of the vents and with the several lock members being controllable by a lower lock member and, with the lower lock member having cam surfaces that are first engaged by a pin carried by crank arms embodied in the vent closing mechanism and whereby the crank arms when movable inwardly in a closing action of the vents, cams the lower locking device upwardly, and through the medium of links between the locking devices, the locking devices are simultaneously swung upwardly so that a locking recess is presented to receive pins carried by the vents when the vents are moved to substantially the fully closed position and, with the lower locking devices being additionally cammed downwardly when the vents have reached their approximately closed position, so that the lower locking devices are forced downwardly, carrying the upper lock devices also downwardly and forcing all of the lock devices simultaneously into locking engagement with the pins carried by the ends of the vents.

The locking devices as above noted also function to be automatically released from the pins of the vents upon the start of the swinging movement of the cranks to move the several vents to an open position, such initial release of the locking devices being necessary and, it should be understood that the initial movement of the cranks and their cam actuating pins permits the cranks to travel a distance capable of camming the lower lock devices upwardly, prior to the movement of the vents outwardly.

Novel features of construction and operation of the device will be more clearly apparent during the course of the following description, reference being had to the accompanying drawings, wherein has been illustrated a preferred form of the invention and wherein like characters of reference are employed to denote like parts throughout the several figures.

In the drawings:

Figure 1 is an outer face view of a window construction, having a plurality of vents and with the vents being shown in section for sake of clearness,

Figure 2 is a horizontal section, taken substantially on line 2—2 of Figure 1,

Figure 3 is a vertical section taken substantially on line 3—3 of Figure 2, and with the window moved to the open position,

Figure 4 is a view similar to Figure 3, but illustrating the window and associated parts in the fully closed and latched position.

2

Figure 5 is a side elevation of an actuating latch, also illustrated in Figures 3 and 4, but illustrating the latch in the initial movement to move the several latches in a direction to release the window vents,

5 Figure 6 is a view similar to Figure 5, but illustrating the actuating latch as shifted to a fully released position and,

10 Figure 7 is a view similar to Figures 5 and 6, but illustrating the initial movement of the actuating latch in the closing movement of the window for shifting the several latches to a position for receiving pins carried by the window vents.

15 Referring specifically to the drawings, the numeral 5 designates extruded jamb forming members, and the numeral 7 indicating an extruded connecting member for the lower ends of the jambs, all preferably formed of aluminum and assembled to form an open frame. The several members each are provided with an inner stop

20 8, forming an abutment for inner flange members 9 of vent frames 10, and with the frames 10 having circumferential flanges 11 that overlie and abut reveal portions

25 12 of the frame members and whereby to effectively weather the vents with respect to the frame when in the fully closed position. Each of the vents, of which there

30 25 may be any desirable number, carry hinge elements 13 at their upper ends, and with the hinge elements 13 being pivotally connected at 14, to operator bars 15, that are vertically slidably under the influence of links 16, pivotally connected at 17 to the operator bars and also

35 30 pivotally connected at 18, to crank arms 19, the construction being duplicated at the opposite sides of the window. The crank arms 19 are fixed upon a cross

40 35 shaft 20, horizontally disposed through the sill member 7 and movable under the influence of a conventional geared operator, not shown. The several vents are

45 40 fulcrumed to swing in a vertical arc to open and closed positions, by fulcrum bars (not shown) and customary in windows of this type. The mechanism so far described is conventional and does not constitute a part

50 45 of the invention. Each of the vents 10 upon their opposite ends, are provided with projecting pins 24, while the cranks 19 are provided with projecting pins 25.

55 50 Pivots connected to the inner spaced wall 7a of the jambs 7 are actuating latches 26. The latches 26 are

60 55 pivoted at 27, to swing in a vertical plane. The latches 26 function to lock the lower vent and to also actuate upper latches to and from a locking position with respect to upper vents. The latches 26 are double faced, embodying upon one side, a downwardly open groove 28,

65 60 having a lower flaring wall portion 29. The groove 28 functions to receive a pin 24 upon the adjacent end of the lower vent and, when the latch is in a fully lowered position, the pin 24 will be fully engaged within the slot 28.

70 65 The opposite side of the latch 26 is provided with a leading beveled edge 30, that extends to a cam groove 31, and with a relatively short dwell portion 32 being disposed between the cam edge 30 and the cam groove 31. The cam edge 30, the dwell section 32 and the groove 31 are

75 70 also disposed in the path of movement of the pins 25 carried by the cranks 19. Upper latches 33, are pivotally supported at 34 upon the wall section 7a and in the same vertical plane as the latches 26. The latches 33 are slotted at 35 and the slots 35 open downwardly to com-

80 75 municate with a bevel surface 36 that receives and cams adjacent pins 24 into the slots 35, should the window be

85 80 partially away from a full seating position and the cam surface 36 effectively cams and pulls the window into snug weathering engagement with the frames. The lower

90 85 actuating latches and one upper locking latch has been

95 90 illustrated although, it will be apparent that additional latches will be employed where additional vents are re-

quired for a particular window structure. The latches 26 and the latches 33 are connected together by elongated links 37, pivotally connected to the latches 26 and 33, as at 38 and 39. It will be apparent, that any movement of the latch 26 will be imparted to the upper latches 33, both to and from a locking position.

In the use of the device, with the parts illustrated, as in Figure 4, when the vents are to be shifted to the open position, the shaft 20 is rotated, causing the cranks 19 to move outwardly. Since in window constructions of this type, there is an initial lost motion between the cranks and the window operating linkage, it follows, with this lost motion, the pins 25 cam against the upper walls of the cam grooves 31, causing the starting release movement of the latches 26, such being shown in Figure 5. A further motion of the cranks 19, causes the pins 25 to swing the latches 26 upwardly, and as in Figure 6, the latches 26 have been moved upwardly sufficient to clear the pins 24 from their respective grooves 28 and 35, permitting the cranks 19 to continue the opening movement of the vents. No means has been provided to retain the latches in the release position other than the usual frictional engagement of the pivotally connected parts thus, there is a possibility that the latches may drop downwardly after the window has been fully moved away. Assuming the latches are in the lower position as illustrated in Figure 3, when the window is being shifted to a closed position, the cranks 19 swing inwardly, causing the operator bars to move upwardly, carrying with them the pivots 14, the hinge elements 13 and swinging the vents downwardly on their fulcrum levers. As the cranks continue their inward movement, it will obviously become apparent that the latches must be moved to an open position to receive the pins 24. To be sure that the latches will be elevated to receive the pins 24, the inward swinging movement of the cranks 19, carrying the pins 25, cause the pins to first engage the cam edge 30, shifting the latches 26 upwardly and, through the linkage 37 moving the upper latches 33 in a corresponding manner, presenting the opening of the grooves 28 and 35 to the line of movement of the pins 24. This initial movement has been shown in Figure 7. When the pin 25 engages the dwell portion 32 of the latches 26, the latches remain relatively stationary to permit of the full closing movement of the vents and, as the pins 25 enter the cam groove 31, they bear against the lower edge of the groove, forcing the latches 36 downwardly upon their pivots 27 and, through the medium of the links 37 force the latches 26 and 33 to move downwardly over their pins 24 to a full seating and locking engagement within the grooves 28 and 35, thus securely holding the several vents at each end against any unauthorized movement outwardly.

It will be apparent from the foregoing that a very novel form of latch means has been provided for effectively latching the opposite ends of vertically swinging vents in a fully closed and weathering condition. The latches are mounted within the well known frames of aluminum awning type windows and offer no interference to the free movement of the conventional mechanism employed to actuate the window mechanism. While the latches have been applied to one specific form of window device, it will be clearly apparent that it is not restricted as to its use and readily adapts itself to substantially all of the vertically swinging awning type window vents. The several latches, including the actuating latches and the upper locking latches are cheap to manufacture and are assembled within a window frame with a minimum of effort.

It is to be understood that the invention is not limited to the precise construction shown, but that changes are contemplated as readily fall within the spirit of the invention as shall be determined by the scope of the subjoined claims.

Having described my invention, what I claim as new and desire to secure by Letters Patent is:

1. A window construction comprising a main frame, upper and lower vent frames for movement into and out of the main frame, vertically movable bars mounted upon the sides of the main frame, hinge elements secured to the vent frames near their upper ends and pivotally connected with the vertically movable bars, vertically swinging cranks arranged near the lower end of the main frame, links pivotally connecting the upper ends of the cranks with the vertically movable bars, means to swing the cranks, upper vertically swinging disc-latches arranged near the lower end of the upper vent frame and disposed adjacent to the sides of such vent frame, lower vertically swinging disc-latches arranged near the lower end of the lower vent frame and disposed adjacent to the sides of the lower vent frame, each upper disc-latch being provided with an upstanding first recess which passes downwardly through the lower edge of such disc-latch, each lower disc-latch being provided upon its inner face next to the lower vent frame with an upstanding second recess which passes downwardly through the lower edge of such lower disc-latch, each lower disc-latch having a cam face leading to the third outer recess, means to pivotally mount the upper and lower disc-latches upon the main frame, upstanding links pivotally connecting the upper and lower disc-latches, pins secured to the sides of the upper vent frame near its lower end and arranged to enter the first recesses of the upper disc-latches, pins secured to the lower vent frame and arranged to enter the second inner recesses of the lower disc-latches, and pins secured to the cranks near their upper ends to enter the third outer recesses of the lower disc-latches.
2. A window construction comprising a main frame, upper and lower vent frames for movement into and out of the main frame, vertically movable bars mounted upon the sides of the main frame, hinge elements secured to the vent frames near their upper ends and pivotally connected with the vertically movable bars, vertically swinging cranks arranged near the lower end of the main frame, links pivotally connecting the upper ends of the cranks with the vertically movable bars, means to swing the cranks, upper vertically swinging disc-latches arranged near the lower end of the upper vent frame and disposed adjacent to the sides of such vent frame, lower vertically swinging disc-latches arranged near the lower end of the lower vent frame, each upper disc-latch being provided with an upstanding first recess which flares downwardly and passes through the lower edge of such disc-latch, each lower disc-latch being provided upon its inner face next to the lower vent frame with an upstanding second recess which flares downwardly and passes through the lower edge of such lower disc-latch, each lower disc-latch being provided upon its outer face with an upstanding third outer recess extending through the lower edge of such lower disc-latch, each lower disc-latch having a cam face leading to the third outer recess, said cam face having a dwell portion, the second and third recesses of each lower disc-latch converging downwardly with relation to each other, means to pivotally mount the upper and lower disc-latches upon the main frame, upstanding links pivotally connecting the upper and lower disc-latches, pins secured to the sides of the upper vent frame and arranged to enter the first recesses of the upper disc-latches, pins secured to the lower vent frame and arranged to enter the second inner recesses of the lower disc-latches, and pins secured to the cranks to enter the third outer recesses of the lower disc-latches.
